ARCH SUPPORT

Everett H. Scott, Akron, Ohio, assignor of one-half to Thomas J. Seibert, Akron, Ohio

Application October 31, 1935, Serial No. 47,566

14 Claims. (Cl. 36—71)

This invention relates to improvements in arch supports of the type constituting devices separate from and adapted to be worn within shoes of ordinary construction.

5 Persons suffering from fallen arches or flat feet frequently cannot endure having the arch of the foot instantly raised to and maintained in its normal position. Consequently, the comparatively rigid or non-yielding arch supports 10 which have little resiliency cause much pain and discomfort to the user. Resilient support as heretofore proposed will sometimes injure the shoe. A device whose resiliency can be adjusted is desirable. Where the support is an arched 15 plate fixed at both ends to a bottom plate arranged as an inextensible chord on the arch, with one end adjustable, while the height of the arch can be varied to suit the particular case, such supports are also comparatively stiff and 20 uncomfortable because the base length or spread of the arch is not automatically varied by a changing application of the user's weight.

The primary object of my invention is to overcome the above-mentioned objectionable features 25 of prior arch supports by providing a support which is highly resilient and more comfortable to the user, and one which is durable and will not injure the shoe in which it is worn. Further objects are to provide improved means of 30 varying the resiliency of the arch support to adapt it for wearers of different weight or various degrees of arch height, or for adjusting it to feet with the arch fallen on one side or the other; to facilitate setting the adjustment 35 when required, and to simplify the structure and reduce its cost of manufacture.

This application is a continuation in part of 40 my prior application Serial No. 19,739, filed May 3, 1935.

45 Of the accompanying drawing, Fig. 1 is a side elevation of an arch support embodying my invention in a preferred form, illustrated in operative position within a shoe indicated by broken lines.

45 Fig. 2 is a bottom plan view of the arch support on a larger scale, partly broken away.

Fig. 3 is a longitudinal section on the line 3—3 of Fig. 2.

50 Fig. 4 is a bottom plan view showing a modification.

Fig. 5 is a longitudinal section on the line 5—5 of Fig. 4.

55 Referring at first to Figs. 1, 2 and 3, 10 indicates the arch support as a whole, including a thin, highly flexible, upper strip-like body hav-

ing a heel portion 11, an arched instep portion 12 extending forward to and including a portion of the ball of the foot, and a horizontal outline adapted to fit snugly within the corresponding portion of an ordinary shoe 13 indicated in broken lines in Fig. 1.

5 The arched upper body of the support in this instance comprises two layers or laminations, namely an upper flexible member or cover layer 14 of a relatively soft, wear-resistant material such as leather, whose edges define the outline of the support, and an underlying flexible metallic layer or member 15 of smaller area, which may be a thin plate of spring steel, secured to the leather cover by a pair of longitudinally spaced rivets 16. The length of the metal plate 15 is such as to underlie the instep bottom or arch of the foot, and its outline substantially follows that of the cover layer.

10 A stretchable spring member 17, underlying 20 the metal plate 15, has its two ends detachably connected with the end portions of said plate, beyond the respective rivets 16, and is arranged as a chord on the arch of the plate 15, its normal or unstressed length being shorter than the 25 distance between its end connections with the plate, so that the spring member is under tension and makes a resilient structure with the plate. The member 17 is preferably made of 30 spring wire and of flat, sinuous or serpentine form, although other substantially flat forms could be used.

15 The end connections between the plate 15 and spring member 17 may be made in various ways, 35 preferably in the manner shown, as by forming a long horizontal hook 18 on the rear end of the spring, engaged with a loop 19 which is struck down from the metal of the plate, this end being non-adjustable; and at the front end by forming an upwardly-directed short hook 20 on the front 40 end of the spring, selectively engaged in any one of a series of holes 21 formed in the plate 15. To avoid substantial protrusion of the end of hook 20 above the surface of the plate, the metal 45 of the latter is drawn down in an annular flange 22 surrounding each of the holes. In place of these flanged apertures, broadly equivalent connecting members could be used, as by repeating the rear-end horizontal hook and plate loop formation at 50 a number of points on the front end, or employing struck-down hook tongues as will be described in the modification, Figs. 4 and 5. The illustrated combination of rear and front connections has the advantage of maximum strength, simplicity, 55 ease of connection at both ends and security at

the rear end when the front-end connection is being changed.

The holes 21 are serially distributed laterally and longitudinally of the plate 15 in an arc which is convex toward the spring 17, for the double purpose of varying the spring tension by advancing the hooked forward end of the spring more or less toward the front end of the plate, and angularly placing the spring toward one side or the other or in the middle, in various relations to the plate, for the correction of foot arches which are correspondingly flattened in different ways. It will be obvious that the number and disposition of the holes could be varied from the particular arrangement shown in Fig. 2, to perform one or the other or both of these functions.

Adjustability of the spring at its front, rather than its rear end is preferred because its above-mentioned angular shifting on a rear pivot affords a wider range of forward support for different conditions of the foot arch, and an undue thickness at the heel end is avoided. The location of the rivets 16 between the front and rear connections of the spring ends avoids contact of their lower heads with the supporting surface.

23 is a bottom plate of a relatively hard and tough non-metallic material such as vulcanized fiber, having its rear end pivotally fixed to the rear end of the metal plate 15 by a rivet 24, and underlying the spring 17. The front end of plate 15 has a sliding bearing on the upper side of this bottom plate to permit the arch of said plate to spread or contract without substantial obstruction and without injuring the shoe. Said bottom plate can be swung aside to permit access to the spring for its application, adjustment or removal.

In operation, the article is worn as indicated in Fig. 1, and then affords a comfortable resilient support for the foot arch, either in standing or walking, by reason of the fact that the base of the arch in the support can spread or contract according to the varying portion of the wearer's weight applied thereto, the front end of the upper body 14, 15 sliding upon the supporting surface. Were this surface only that of the comparatively soft insole of the shoe, the sliding forward movement of the front end of the metal plate 15 would be obstructed and the insole would be injured by scuffing, but the vulcanized fiber bottom plate 23 presents a hard wearing surface readily permitting this sliding action without substantial obstruction, or injury to the shoe. To adjust the tension of spring 17 to the wearer's weight or to the different degrees of foot correction required, it is only necessary to swing aside the bottom plate 23 and place the hooked ends 20 of said spring in a different one of the holes 21, either in the middle or on one side or the other as conditions may demand.

60 In the modification illustrated in Figs. 4 and 5, the metal plate 15 of the arched upper body is of smaller area and is attached by rivets 16 between upper and lower layers 14, 25 of leather or equivalent material included in said upper body.

65 An underlying serpentine wire spring 17, arranged as a chord on the arch, is fixedly secured at its front end to the leather layers by another rivet 16^a, and at its rear end is detachably and adjustably connected with the plate 15 by a hook 26 on the spring, engaging any one of a longitudinal series of hook tongues 27 struck down from the metal of the plate and projecting through an aperture 28 formed in the lower layer 25. In this embodiment, the bottom plate of Figs. 1 to 3 is omitted, subject to greater liability of the sup-

port to be obstructed in the sliding movements of its front end or to injure the shoe insole by contact with the latter, but it will be obvious that such an element could be added.

Other changes of embodiment may be effected 5 without departing from the scope of my invention as defined in the claims.

I claim:

1. An arch support comprising a bottom plate, a flexible arched upper body slidable on one end of said bottom plate to spread or allow contraction of the arch by the varying weight of the user applied thereto, and fixed on the other end of said bottom plate, and an intervening, extensible spring member connected at its ends to the upper 15 body and arranged as a chord thereon.

2. An arch support according to claim 1 in which the spring member is detachably and adjustably connectible at one end with the upper body at a plurality of points on the latter, and 20 the bottom plate is pivoted at its fixed end to the upper body and adapted to be swung aside to afford access to the adjustable connection.

3. An arch support according to claim 1 in which the upper body includes a spring metal 25 plate and the bottom plate is flexible and of a relatively-hard, non-metallic material such as vulcanized fiber.

4. An arch support comprising a flexible arched body automatically slidable at its front end on 30 a supporting surface and normally free to spread or allow contraction of the arch by the varying weight of the user applied thereto, and an underlying extensible spring member arranged as a chord on said body, having a fixed attachment 35 thereto at one of its ends and adjustably connectible at its other end to the body at a number of different keeper points on the latter.

5. An arch support according to claim 4 in which the points of connection of the spring 40 member at its adjustable end are longitudinally distributed on the body to vary the tension of said member.

6. An arch support according to claim 4 in which the points of connection of the spring 45 member at its adjustable end are laterally distributed on the body to vary the angular relation between said member and body.

7. An arch support according to claim 4 in which the body has a series of points of connection with the spring member, laterally arranged on the body in an arc which is convex toward 50 said member to vary the latter's tension and its angular relation to the body.

8. An arch support comprising a flexible arched 55 plate formed near one end with a series of keeper holes and automatically slidable at its front end on a supporting surface to spread or allow contraction of the arch by the varying weight of the user applied thereto, and a wire spring member 60 arranged as a chord on said plate, having one end connected with the plate and its other end upwardly bent as a hook to selectively engage in said holes.

9. An arch support according to claim 8 in 65 which the plate is annularly flanged downwardly around each of the holes to prevent substantial protrusion of the hooked end of the spring member above the upper surface of the plate.

10. An arch support comprising a thin, highly- 70 flexible, strip-like body having heel and arch portions and formed of at least two layers of material securely fastened together, means including an elastic member arranged longitudinally of and at the under side of said body for adjustably 75

upwardly arching and varying the resiliency of the intermediate portion of said body, said means further embodying devices for selectively connecting one end of said elastic member to said body at different distances from the corresponding end of the body so that the tension of said elastic member is varied, and a further layer of material disposed beneath said elastic member to prevent said elastic member from coming in contact with the bottom of the shoe in which said arch support is worn, said further layer of material being pivotally attached at one end to said body to permit ready access to and adjustment of said elastic member.

15 11. An arch support comprising a flexible arched upper body slidable at its front end on a supporting surface, an underlying tension spring fixed at its rear end to said body, and adjustable fastening means at the front end of said spring 20 making it selectively connectible at its front end to the body at a number of different points on the latter.

12. An arch support according to claim 11 in which the front-end connecting points are laterally distributed to vary the angular relation between the body and spring.

13. An arch support comprising a flexible arched upper body composed of two layers of non-metallic material of which the lower one is 30 formed with an opening, an interposed metal

plate formed with a series of spring-connecting devices exposed through said opening, and an underlying tension spring having one end connected with said upper body and its other end formed with a hook selectively connectible with 5 said devices.

14. An arch support comprising a thin, highly flexible, strip-like body having heel and arch portions and formed of two layers of material secured together, the lower layer having an opening in the heel portion thereof, a metallic plate secured between said layers and having downwardly extending keeper hooks exposed through said opening in the lower layer and arranged in a longitudinal series, and an elastic member 15 arranged longitudinally of and at the under side of said body and attached at one end to the corresponding portion of said body, said elastic member having means at its other end for selectively connecting said other end to a desired 20 one of said keeper hooks whereby the tension of said elastic member may be varied and a desired upward arching of the arch portion of the body effected, with a corresponding regulation of the resiliency of said arch portion, said elastic member comprising a spring formed of a piece of 25 spring wire with serpentine bends and having one end formed into a hook for engagement with said keeper hooks.
